UNITED STATES PATENT OFFICE

2,519,710

RACK ACTUATED ROUNABOUT TOY

Charles J. Slatrow, Waltham, Mass.

Application June 27, 1946, Serial No. 679,786

5 Claims. (Cl. 74—167)

1

This invention relates to a toy and more particularly to a spinning toy.

The primary object of the invention is to afford amusement and entertainment for children and grownups alike.

Another object is a toy simulating action, and particularly the action of race horses traveling around a track.

A further object is manually to impart rotary motion to a rotor through the medium of a novel pump.

The above and other objects may be attained by employing this invention which embodies among its features a stator or base, a rotor rotatably mounted on the stator, a toothed drive wheel having driving connection with the rotor, a lever pivoted to the stator, an arm pivoted to the lever and a rack on the arm adapted to be moved into driving relation with the toothed drive wheel by movement of said lever in one direction about the pivot, and simultaneously by the movement of the arm about its pivot to impart rotary motion to the drive wheel and consequently to the rotor.

Other features include objects mounted on the stator simulating natural or artificial objects, and objects mounted on the rotor simulating natural objects so that as the rotor is rotated the motion of the objects thereon will be accented by the stationary objects on the stator.

Other features include finger grips on the lever and on the arm automatically to advance the rack into engagement with the toothed wheel and swing the arm about its pivot in a direction to drive the toothed wheel and means to retract the lever and move the rack out of driving relation with the drive wheel.

Still other features include signal means to indicate audibly the end of the travel of the rack.

In the drawings,

Figure 1 is a top plan view of a toy embodying the features of this invention.

Figure 2 is a side view thereof.

Figure 3 is a horizontal sectional view taken substantially along the line 3—3 of Figure 2.

Figure 4 is a transverse sectional view taken substantially along the line 4—4 of Figure 1.

Figure 5 is a fragmentary enlarged sectional view through the device, and

Figure 6 is a horizontal sectional view taken substantially along the line 6—6 of Figure 5.

Referring to the drawings in detail, a base or stator 10, preferably circular in plan is provided adjacent its periphery with upstanding legs or

posts 11 simulating fence posts to which an annular rail 12 is attached, to define a circular path within the confines of which the rotor operates. Carried centrally of the base or stator 10 is a socket 13 in which a bearing bushing 14 is fitted. This bearing bushing supports a column 15 provided at its upper end with external screw threads 16 upon which is supported an inverted socket 17 formed at its lower end with a conical base member 18.

Secured in any suitable manner to the underside of the conical member 18 is a platform 19, and the edge of this platform is arranged in concentric spaced relation to the periphery of the stator 10 as will be readily understood upon reference to the drawings. Formed at spaced intervals about the periphery of the platform 19 are upstanding posts 20 carrying at their upper ends a rail 21, the upper edge of which lies in substantially the same plane with the upper edge of the rail 12 previously described.

Rotatably supported on the bearing bush 14 between the underside of the platform 19 and the upper side of the base or stator 10 is a toothed drive wheel 22 to the hub 23 of which is secured a rotor designated generally 24. The rotor 24 comprises a circular plate 25 the periphery of which is disposed between the rails 12 and 21 and the posts 11 and 20, and fixed adjacent the periphery of the plate 25 are suitable figures 26 which in preferred form simulate race horses mounted by jockeys 27.

Pivottally supported as at 28 in eccentric relation to the column 15 on the base or stator 10 is a lever 29 provided with a thumb or finger-piece 30 which projects beyond the peripheral edge of the stator 10 to facilitate manipulation of the device by the fingers of the user. Projecting laterally from the lever 29 intermediate its ends is an ear 31 adjacent the end of which is pivoted as at 32 an arm 33 carrying at its inner end a toothed arcuate rack bar 34 the teeth of which are adapted to mesh with the teeth of the toothed drive wheel 22 under certain conditions to be more fully hereinafter explained. Formed on the end of the arm 33 opposite the rack bar 34 is a thumb or finger-piece 35 which cooperates with the thumb or finger-piece 30 previously described during the operation of the device. Attached in any suitable manner to the base or stator 10 is one end of a retractile coil spring 36, the opposite end of which is connected as at 37 to the arm 33 near its pivot point, but slightly off-set therefrom toward the center of the stator or base 10. A bell or like audible warn-

ing signal is mounted on the base 10 in the path of movement of the rack bar 34 adjacent the end of its power stroke so as to audibly indicate the completion of the power stroke thereof.

In operation, it will be understood that the thumb or finger-pieces 30 and 35 are grasped between the thumb and forefinger, and the pieces pinched together as suggested in the dotted line position illustrated in Figure 3. The act of pinching the members 30 and 35 will cause the lever 29 to swing about its pivot 28 so as to advance the rack 34 into meshing engagement with the teeth of the drive wheel 22, and simultaneous movement of the lever arm 33 about its pivot 32 will impart a swinging motion to the rack and transmit this motion to the toothed drive wheel 22 so as to cause the wheel and the disc 25 carried thereby to rotate about the bearing bushing 14. Such movement will extend the spring 36, and the completion of the power stroke of the rack will be audibly indicated by the contact of the end of the rack with the bell 37, and the parts upon release of the thumb or finger-pieces 30 and 35 will be restored to their initial position under the influence of the spring 36. Since the spring 36 tends to move the lever 29 in a direction which will retract the arm 33, it will be obvious that the parts will return to initial positions without in any way interfering with the spinning of the wheel 22 and its attendant mechanism. From the above it will be evident that I have provided a novel mechanism by which spinning toys in general may be driven, and the driving rack will only contact the drive wheel during the power stroke thereof.

While in the foregoing there has been shown and described the preferred embodiment of this invention it is to be understood that minor changes in the details of construction, combination and arrangement of parts may be resorted to without departing from the spirit and scope of the invention as claimed.

I claim as my invention:

1. A device comprising a stator, a rotor rotatably mounted on the stator, a toothed drive wheel having driving connection with the rotor, a lever pivoted to the stator, an arm pivoted to the lever, a rack on the arm adapted to be advanced into driving relation with the toothed drive wheel by movement of said lever in one direction about its pivot and to be retracted from driving relation with the drive wheel by movement of the lever in a reverse direction, and finger grips on the lever and the arm which when advanced toward one another progressively and sequentially advance the rack into engagement with the toothed wheel and swing the arm about its pivot in a direction to drive the wheel.

2. A device comprising a stator, a rotor rotatably mounted on the stator, a toothed drive wheel having driving connection with the rotor, a lever pivoted to the stator, an arm pivoted to the lever, a rack on the arm adapted to be advanced into driving relation with the toothed drive wheel by movement of said lever in one direction about its pivot and to be retracted from driving relation with the drive wheel by move-

ment of the lever in a reverse direction, finger grips on the lever and the arm to advance the rack into engagement with the toothed wheel and swing the arm about its pivot in a direction to drive the wheel, and means to move the lever in the reverse direction and retract the rack out of driving relation with the wheel.

3. A spinning toy comprising a stator, a rotor rotatably mounted on the stator, a toothed drive wheel having driving connection with the rotor, a lever pivoted to the stator, an arm pivoted to the lever, a rack on the arm adapted to be moved into driving relation with the toothed drive wheel by movement of said lever in one direction about its pivot, cooperating finger grips on the lever and on the arm which when advanced toward one another progressively and sequentially advance the rack into engagement with the toothed wheel and swing the arm about its pivot in a direction to drive the wheel, and a retractile coil spring connected to the stator and to the arm yieldingly to move the lever and the arm about their respective pivots and retract the rack from wheel engaging position.

4. A spinning toy comprising a stator, a rotor rotatably mounted on the stator, a toothed drive wheel having driving connection with the rotor, a lever pivoted to the stator, an arm pivoted to the lever, a rack on the arm adapted to be moved into driving relation with the toothed drive wheel by movement of said lever in one direction about its pivot, cooperating finger grips on the lever and on the arm which when advanced toward one another progressively and sequentially advance the rack into engagement with the toothed wheel and swing the arm about its pivot in a direction to drive the wheel, and signal means secured to said stator, said signal means being selectively struck by one end of the rack when it has completed its wheel driving stroke.

5. A spinning toy comprising a stator, a rotor rotatably mounted on the stator, a toothed drive wheel having driving connection with the rotor, a lever pivoted to the stator, an arm pivoted to the lever, a rack on the arm adapted to be moved into driving relation with the toothed drive wheel by movement of said lever in one direction about its pivot, a retractile coil spring connected to the stator and to the arm yieldingly to move the lever and retract the rack from wheel driving relation, and signal means secured to said stator, said signal means being selectively struck by one end of the rack when it has completed its wheel driving stroke.

CHARLES J. SLATROW.
